UNITED STATES PATENT OFFICE.

ROY E. STEWART, OF BRENTFORD, SOUTH DAKOTA.

ROAD SCRAPER.

Application filed March 27, 1926, Serial No. 97,883. Renewed March 15, 1928.

This invention relates to a machine or implement for operating on roads and particularly to a road drag or scraper. As is well known, the highways are now regularly worked by operatives so as to be kept in proper condition. As the road deteriorates and becomes damaged by the weather, holes or ruts are often formed therein, dirt is washed away from one place and piled up in another. It is desirable, therefore, to have a machine or drag which can readily be manipulated so as to be used to fill up holes or ruts and to either deposit material at one place or remove the same.

It is an object of this invention, therefore, to provide a road drag or scraper having co-operating pairs of blades, the blades of said pairs being inclined at an angle to each other, together with means for swinging said blades about horizontal axes.

It is a further object of the invention to provide a road drag or scraper having a frame, a pair of blades at the forward portion thereof, diverging outwardly and forwardly and also having a pair of blades at the rear portion diverging outwardly and rearwardly, all of said blades having means for swinging the same about horizontal axes parallel to their lengths and means for holding the blades in various positions.

It is still another object of the invention to provide extensions for certain blades of each pair, whereby the blades can be made to overlap the other blade of the respective pair.

These and other objects and advantages of the invention will be fully set forth in the following description made in connection with the accompanying drawings, in which like reference characters refer to similar parts throughout the several views and in which:

Fig. 1 is a plan view of the device;

Fig. 2 is a vertical section taken on line 45 2-2 of Fig. 1 as indicated by the arrows; and

Fig. 3 is a partial plan view showing the traction connection for the device.

Referring to the drawings, a road drag or scraper is shown comprising a frame having horizontal and parallel front and rear members 5 connected at their ends by the parallel side members 6. While the members 5 and 6 may be made of any desired material, in the embodiment of the invention illustrated they are shown as made from

angle bars. The members 6 are connected substantially midway of their lengths by a pair of members 7 illustrated as angle bars, having their vertical flanges in contact. The members 5 and the forward members 7 have extending therebetween a pair of parallel bars 8 also illustrated as angle bars, which members 8 are bolted or riveted to the members 5 and 7. Another pair of parallel bars 9 also extend from the forward member 7 to the member 5, being shown as angle bars and bolted or riveted to the members 5 and 7. The members 8 and 9 incline forwardly and toward the center of the machine, thus forming pairs of forwardly converging bars. A pair of parallel angle bars 10 also extend from the rear member 7 to the rear member 5 and another pair of bars 11 shown as angle bars extend from the rear members 7 to the rear members 5, being bolted to said members and the bars 10 and 11 incline rearwardly and toward the center of the frame, the inner bars 10 and 11 meeting in a point at the rear central portion of the member 5. As shown, the bars 8, 9, 10 and 11 have vertical flanges and sides, and a link 12 depends from one each of said bars, being pivoted to the vertical flange thereof, and having its lower end bent laterally and riveted to an angle member 13. A lever 14 is also pivoted to one each of the bars 8, 9, 10 and 11, and particularly to the outer bar, which lever is also bent laterally at its lower end and riveted to the angle bar 13, which latter bar extends horizontally. Each angle bar 13 has a blade member 15 riveted thereto. While the blades 15 may be variously formed and made, in the embodiment of the invention illustrated they are shown as flat metal plates. The levers 14 extend above the bars to which they are pivoted and each has a link 16 pivotally connected to its upper end extending rearwardly and pivoted to the intermediate portion of an upstanding lever 17. The levers 17 are pivoted respectively to the outer bars 8, 9, 10 and 11 and move alongside of notched segments 18 also secured to said bars. The levers 17 have handles at their upper ends and a pawl grip 105 handle 19 is pivoted to each of said levers connected by a link 20 to a pawl 21 guided in a lug 17^a on the levers 17 and adapted to seat in the notches 18^a of the segment 18 a spring 22 preferably being disposed between the handles 19 and lever 17 tending to hold the pawl 21 in engaged position. It

110

will be noted that the blades 15 at the forward portion of the frame have their inner ends spaced and said blades diverge forwardly and outwardly, one of said blades, as 5 illustrated that shown at the right of Fig. 1, has an extension portion 24 bolted thereto which extend past the inner edge of the other forward blade 15, said extension blade being readily removable and held in place 10 by headed and nutted bolts. The rear blades 15 as shown, diverge outwardly and rearwardly and one of said blades has its inner end extending past the inner end of the adjacent blade and curved somewhat 15 around the latter. A seat 25 is carried on an upwardly extending bar 23 secured to the forward member 7 substantially at the center thereof.

The forward member 5 has spaced eye-bolts 26 secured therein, between which extends a chain 27 having its ends secured in said eye-bolts. The chain 27 is of the ordinary straight link type and a loop member 28 is provided through which the chain 25 passes, said member 28 having a ring 28^a at one end and an elongated loop portion 28^b with parallel sides at its other end, the plane of the portion 28^b being substantially at right angles to that of the ring 28^a.

30 In operation the device will be hitched by means of member 28 to suitable traction means such as horses or a tractor, and drawn along with the blades 15 in contact with the surface of the road. It will be noted that 35 member 28 can be disposed at different points along the chain 27, the lower portion 28^b of member 28 engaging in the angle between adjacent links and thus exerting a pull on the chain. The chain can thus either 40 be pulled from the center or from some lateral point. It is often desirable to connect the chains at some lateral point to give a side hitch to the device, as when operating on the side of a sloping road.

45 If it is desirable to move considerable dirt with the forward blades 15, they will be disposed in the vertical position or with their top edges inclined somewhat rearwardly by adjustment of the levers 17. They will 50 thus carry the dirt from the sides of the road and other portions inwardly. This dirt will pass out between the inner ends of the bolts and will be distributed as desired by the rear blades 15. If a long rut is to be filled 55 up, the rear blades 15 can be disposed with their top edges directed forwardly and the dirt delivered by the front blades will thus be disposed in a rather long ridge. If it is desired to distribute the dirt more evenly, the 60 blades 15 can be brought to a more nearly vertical position. The amount of dirt taken from the road by the forward blades can thus be nicely determined by adjustment of said blades by their levers 17.

65 If it is desired to move dirt to the sides

of the road from the center of the road, the forward blades 15 will be swung with their top edges directed forwardly and will move very little dirt. The rear blades can then be set in vertical or rearwardly inclined position and will thus move the dirt from the center of the road to the edges. By inclining both sets of blades rearwardly and using the extension blade 24, an uneven road can be nicely leveled, as both sets of 70 blades move thereover. As the rear blades are supposed to move all of the dirt and not let any pass between their inner edges, one of the blades extends around the end of the other, thus forming a continuous dirt 75 engaging surface. The blades can be quickly adjusted by the operator and with the various adjustments a very universal drag and road scraper is provided, and one which can be used to take care of all operations which 80 are necessary on the road.

It may be further noted that when the extension 24 is used the blades 15 at the left and front of the device, and the blade 15 at the right and rear of the device can be thrown backward so as to have practically no effect, and the other blades will then form substantially a continuous blade extending diagonally across the machine. The scraper then operates with one long diagonal blade 95 and all of the dirt is moved one way. The extension, of course, can also be placed on the blade 15 at the left and front of the device and will co-operate in a similar manner with the blade at the right and rear of the device.

It will also be noted that the device can be used with one of the forward blades or one of the rearward blades inclined backward so as to have little effect, and the blade either at the front or rear held in vertical position so that only the blades or blade at one side of the machine has a scraping or drag effect. The device is thus capable of many uses, and as stated above can take care of all necessary operations on the road surface.

From the above description it is seen that applicant has provided a very simple and efficient road drag and scraper and one having great utility for the use intended.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:

1. A road drag or scraper having in combination, a frame, a pair of blades diverging forwardly toward their outer ends and separated in overlapping relation at their inner ends, means for swinging said blades about 120

125

130

horizontal axes and for holding said blades in various positions, a pair of blades diverging rearwardly toward their outer ends in the rear of said first mentioned blade and means for swinging said latter blades about horizontal axes and for holding said blades in various positions.

2. The structure set forth in claim 1, and one of said latter blades having an extension at its inner end projecting past the inner end of the other blade of said bar.

3. The structure set forth in claim 1, one of said first mentioned blades having a readily detachable extension secured to the inner end thereof and extending past the inner end of the other blade of said bar.

4. A road drag or scraper having in combination, a frame, a pair of blades at the forward portion thereof diverging forwardly toward their outer ends and separated at their inner ends, means for swinging each of said blades about a horizontal axis respectively parallel therewith and above said blade, means for holding said blades in various positions, a pair of blades at the rear portion of said frame diverging rearwardly toward their outer ends and overlapping at their inner ends, means for swinging each of said latter blades about a horizontal axis extending substantially parallel therewith and above said blades, and means for holding said latter blades in various positions.

5. A road drag or scraper having in combination, a rectangular frame having converging pairs of parallel bars at each side thereof at its forward portion, a blade disposed beneath each pair of said bars and

respectively substantially at right angles to said bars, members rigidly secured to said blades and extending upwardly and pivoted to said bars about a common horizontal axis, one of said members being extended to form a lever, means for moving said levers and holding the same in various positions, said frame having pairs of rearwardly converging parallel bars at its rear portion, a blade disposed beneath each pair of said bars and extending substantially at right angles thereto, members rigidly connected to said blades extending upwardly therefrom and pivotally connected to bars of each pair, one of said members of each pair being extended to form a lever and means for moving said levers and holding the same in various positions.

6. The structure set forth in claim 1, the first mentioned pair of blades making the same angle with the longitudinal center line of the machine as said last mentioned blades.

7. A road drag or scraper having in combination, a frame, a pair of blades at the front portion of said frame and depending therefrom in contact with the ground for moving dirt toward the center of said frame, and a pair of blades in the rear of said blades depending from said frame into contact with the ground, and diverging toward their outer ends, one of said blades having a portion overlapping the inner end of said other blade and means on said frame for swinging said latter blades about a horizontal axis and holding the same in adjusted position.

In testimony whereof I affix my signature.
ROY E. STEWART.
